UNITED STATES PATENT OFFICE

EMMERY J. H. BUSSARD, OF CINCINNATI, OHIO, ASSIGNOR TO THE CROSLEY RADIO CORPORATION, OF CINCINNATI, OHIO, A CORPORATION OF OHIO

VACUUM-TUBE CIRCUITS

Application filed July 27, 1925. Serial No. 46,258.

My invention relates to vacuum tube circuits and particularly to circuits known as "reflex" circuits, where the same tubes are used for both radio and audio frequency amplification.

A known way of reflexing in vacuum tube circuits is to place the secondary of an audio frequency transformer in series in the lead connecting the input radio frequency circuit 10 to the filament circuit, and impressing upon the primary of the transformer the audio frequencies from a subsequent rectifying element of the hook up.

In such a structure the probabilities are 15 that the audio transformer secondary causes the tube in whose input circuit it is in series to rectify, due to the very great impedance of the secondary to the radio frequency currents. At any rate such an arrangement cuts 20 down the amplitude of the radio frequency currents in the plate circuit of the tube.

It has been the practice in some cases where it was desirable to amplify or repeat an audio frequency current, to use two vacuum tubes 25 with the in-put to the grids arranged 180 degrees out of phase, thereby resulting in a balancing effect on the plate circuit currents, due to the fact that there would be no variations in the plate circuits due to unequal actions of the tubes during periods of positive 30 and negative audio frequency current, because one tube would have a positive and one a negative grid simultaneously.

It is my object to provide for a similar 35 arrangement of tubes to that last above mentioned, but for an entirely different purpose, namely to eliminate the high frequency alternations in the secondary of the transformer used in imposing audio frequencies on the 40 tuned radio frequencies of the pair of tubes, and in connection with the output circuits of the pair of tubes, to duplicate the relation of the input circuits, thereby cancelling the effect of the reflexed audio frequency currents 45 in the plate circuits, of the pair of tubes, so far as concerns their effect on the common radio frequency transformer in the two output circuits, while at the same time utilizing the audio frequency currents in a subsequent 50 stage of audio frequency amplification.

I will defer further explanation of my invention until I have described a typical circuit in which my invention will be of value, which circuit or circuits I will specifically describe and in which it will be noted that 55 I employ a pair of tubes in reflexing which are connected out of phase as to radio frequencies, and in in-phase parallel relation to reflexed audio-frequencies, and in directly opposing relation so far as concerns audio 60 frequency coupling of the radio frequency output circuit to subsequent stages of rectification or further amplification.

In the drawing:

Figure 1 is a diagram of one form of 65 hook up.

Figure 2 is a diagram of another form of hook up.

Referring first to Figure 1 it will be noted that the incoming signals are impressed upon 70 the primary 1, and that the opposite ends of the secondary 2 are connected to the grids 3 and 4 of two thermionic tubes. A lead 5 from the middle of the secondary 2 has the secondary 6 of an audio frequency transformer in 75 series with it and the lead 7 to the filament circuit of the two tubes.

The common lead 5, 6, 7 is the common return of the grid circuits to the two tubes, and a tuning condenser 8 may be connected across 80 the two grid circuits.

In the two tubes the filaments are shown at 9, and the plates at 10 and 11.

A primary 12 is connected to the two plates, and from the primary central point a common 85 return lead for the two plate circuits as at 13, has an audio transformer primary 14 in series therewith. Thus the two tubes have their input and also their output circuits connected 180 degrees out of phase.

I show a detector tube with grid 15, filament 16 and plate 17. The grid has impressed upon it, a radio frequency voltage by means of the secondary 18, which is coupled with the primary 12. The plate circuit with 95 lead 19 has in series therewith the primary 20 which is coupled with the secondary 6 forming an audio frequency transformer with the core 21.

An audio frequency amplifying tube is 100

shown with a grid 22, a filament 23 and a plate 24. The grid circuit has its lead 25 with the secondary 26 in series therewith, which secondary is coupled with the primary 5 14 forming an audio frequency transformer with the core 27.

As so connected the circuits described act as follows. The incoming signal is impressed upon the grids of the paired audions in 180 degrees out of phase relation, and the lead 10 in common to the two grid circuits, comprising leads 5 and 7 and the secondary 6, instead of having a rapidly pulsating current therein, has a substantially steady current 15 due to the out of phase relation, thereby cutting down the rectifying action of this secondary.

The plate circuits of the two paired tubes, whereas they act out of phase on the primary 20, pass in opposite directions from the ends 20 of the primary to the middle, so that the radio frequency currents have a common inductive effect on the secondary of the rectifying tube grid or input circuit.

25 The rectifying tube plate circuit impresses on the primary 20, an audio frequency which is inductively effective on the secondary 6, thereby reflexing the audio frequency on the two paired tubes, but in this instance the 30 audio frequencies are in phase in the two grid or input circuits, as are the resulting audio modulations in the two plate circuits or outputs of the paired tubes.

35 The amplified audio frequencies in the primary 12, which are so built up have no inductive effect on the secondary 18, however, because they flow in opposite directions from ends to the middle of the primary 12, thus 40 cancelling the inductive effects of each other on the secondary 18.

45 However, in the primary 14, the output audio frequencies are in phase with each other and thus impress upon the secondary 26 in the grid circuit of the audio amplifying tube, the amplified audio frequencies which were reflexed back from the detector unit.

50 Instead of cutting down the impressed voltages in the grid circuits of the paired tubes to half the voltage of a full connection, the result of connecting the grids each to but one half of the input secondary gives a good deal more than half the voltage on each grid. This arises from the fact that 55 with the grid circuits of high impedance of the type as shown, and a tube of the usual low input impedance to be found in commercial tubes of the present day, there is a better balance of impedances where only a portion 60 of the input secondary is used than where all of it is used.

65 In the circuit shown in Figure 2 the input secondary 40 is connected from a middle point by leads 41 and 42 with a series connected audio transformer secondary 43 be-

tween them, to the filament circuit lead 44. The two ends of the secondary 40 are connected to the grids 45 and 46 of the paired audion tubes. The plates of these tubes are connected to the primary 47 of the radio frequency transformer whose secondary is in the rectifying input circuit. 70

The phones 48 in series from the common lead 49 from the middle point of the transformer primary 47 to the filament circuit lead 75 44 are sensitive to audio frequencies only. The primary 50 which together with the secondary 43 and the core 51 make up the reflexing audio frequency transformer, is in the output circuit of the rectifying device. 80

I have not drawn out the rectifying circuits as these have been shown in Figure 1, and this second hook up differs from the first in that there is no stage of audio frequency amplification except that which is provided 85 by the reflexed tubes.

In each instance the pair of audions are connected out of phase for radio frequency amplification, and in phase for audio frequency amplification with the result that the 90 audio frequencies are out of phase in the input and output radio frequency transformers and the radio frequencies are out of phase in the input and output audio frequency transformers. I do not find that there is any unsymmetrical action of the paired tubes due to 95 the audio frequencies being sent through the paired circuits in inphase parallel relation.

In the claims, it will be understood that a single audion with two plates and two grids 100 is considered the equivalent of two audions of the usual three electrode type.

Having thus described my invention, what I claim as new and desire to secure by Letters Patent, is:—

1. In an audion amplifier, two audions connected in out-of-phase parallel relation for radio frequency amplification, and in-phase parallel relation for audio frequency amplification, the plate terminals of said tubes connected each to opposing terminals of a radio frequency inductance, the center point of said radio frequency inductance being connected through a device sensitive to audio frequency signals, and a source of 115 plate potential to the common filament circuit of the said audion tubes, means for rectifying and amplifying the modulated radio frequency current in the said plate inductance and impressing the resulting audio frequency current on the primary of a transformer, the secondary of which is connected in the common grid filament lead of the said audion tubes. 120

2. In an audion amplifier, two audions connected in out-of-phase parallel relation for radio frequency amplification, and in in-phase parallel relationship for audio frequency amplification, the plate terminals of said tubes connected to opposing terminals 125 130

of a radio frequency inductance, a center tap of said radio frequency inductance being connected through an audio frequency impedance and a source of plate potential to the common filament circuit of said audions, means for amplifying and rectifying the current of said plate circuit and impressing the resulting audio frequency voltage by means comprising a reactance, upon the common 10 grid-filament lead of the said audion tubes.

3. In an audion amplifier, two audions connected in out-of-phase parallel relation for radio frequency amplification, and in in-phase parallel relation for audio frequency 15 amplification, the plate terminals of said tubes connected to opposing terminals of a radio frequency transformer, a center tap of said radio frequency transformer being connected through the primary of an audio frequency 20 transformer and a source of plate potential to the common filament circuit of said audions, means for amplifying and rectifying the current in said plate circuit and impressing the resulting audio frequency 25 voltage upon the primary of a transformer, the secondary of which is connected to the common grid-filament lead of the said audion tubes.
